FLOAT SUPPORTED TANK CLEANING DEVICE

Granville M. Carr, Wichita, Kans.

Application August 9, 1950, Serial No. 178,513

8 Claims. (Cl. 259—110)

1

My invention relates to a device for cleaning basic sediment from oil tanks. This device is designed for use in the large tanks having capacities of fifty-five thousand barrels or more. In tanks of this kind that are used for storage of crude oil, basic sediment such as paraffine mixed with other materials that are in the oil as it is pumped from the well will separate from the oil and settle to the bottom of the tank in a substance similar to gelatine or soft soap, and after the tank has been in use for some time and has been filled and emptied a number of times, the basic sediment accumulates in the tank and eventually occupies a large percentage of the volume of the tank and if possible must be removed from the tank in order to maintain adequate storage space for the oil being pumped from the wells. The basic sediment has been hard or almost impossible to remove from the tanks and therefore has been so expensive to move that many times it hasn't been moved and the storage space has been lost.

In view of this trouble I have provided my tank cleaning device which is designed to stir up the oil in the tank and set it into circulatory motion in the tank whereupon sediment, sand and the like still in suspension in the oil will rub or scrape on the upper surface of the settled basic sediment and wear it away and remix or suspend it in the circulating oil which may then be pumped from the tank to the oil refinery or other suitable place of use or dispersal. This process of cleaning the tank will finally leave the tank free and clean of the basic sediment and regain the oil storage space that had been lost.

A further object of my invention is to provide a device of the kind mentioned that is safe to place and operate in a tank of oil as the mechanism is one in which no sparks or flashes of any kind are developed that might set fire to the oil or vapors rising therefrom.

A still further object of the invention is to provide a device of the kind mentioned whose parts are small enough that they can be taken through the man-hole in the top of the tank and then assembled inside the tank to provide the complete machine that is ready for use.

A still further object of the invention is to provide a device of the kind mentioned whose source of power for the operation of the machine is outside and a safe distance from the tank and may be mounted as a truck that may be moved from the tank to tank whereby the same power unit may be used to operate several stir-

ring units, one after the other in several different tanks.

A still further object of the invention is to provide a device of the kind mentioned that is compact, inexpensive, simple in construction, sturdy and long lived, one that is highly efficient in its work as well as one that is simple and easy to handle and operate. These and other objects will be more fully explained as this description progresses.

Sometimes the inner surface of the walls of the tank will corrode and this corrosion must be removed in order to put the tank in best condition for further use. This cleaning of corrosion can be easily accomplished by placing water and sand in the tank and employing my circulating device to put the water and sand in a circulatory motion in the tank whereby the sand will scour the rust from the walls of the tank and leave the walls in a clean condition.

There are many other advantageous processes that can be carried on by the circulating of liquids in the tank, all of which can be achieved by the use of my liquid circulating device, such as separating oil and water etc.

Now referring to the accompanying drawings in which similar numerals of reference designate the same parts throughout the several figures of the drawings; Fig. 1 is a top plan view of a large tank, a part of the top cover of the tank is broken away to show my improved circulating device in working position in the tank.

Fig. 2 is a vertical sectional view through the tank and showing my improved circulating device, the view being as seen from the line II—II in Fig. 1 and looking in the direction of the arrows.

Fig. 3 is an enlarged detail perspective view of the circulating device and associated parts.

Fig. 4 is an enlarged detail perspective view of a stop element employed in preventing the device from floating away in the circulating movement of the oil in the tank.

Fig. 5 is a side view of one of the float elements employed in supporting the impeller and power driving unit therefor, the view being as seen from the line V—V in Fig. 6 and looking in the direction of the arrows.

Fig. 6 is an end view of one of the pairs of float elements employed in supporting the impeller and power driving unit therefor.

Fig. 7 is a side view of a modified form of device for tightening the stabilizer line.

In the drawings is shown a large conventional circulator steel oil tank 10 having a cone shaped

cover 11 thereover and in which is a manhole 12 that is located close to the vertical wall of the tank 10. The tank 10 is provided with a ladder 13 that is built on the outside of the tank wall 10 and extends from the ground to the top of the tank and adjacent the man hole 12. The tank 10 is also provided with a second ladder 14 that is located inside the tank 10 and is rigidly attached to the inside face of the wall of the tank 10 and extends from the bottom to the top of the tank 10 immediately at the manhole 12. The tank top 11 is provided with a man hole cover, not shown, whereby the manhole 12 may be closed to avoid rain, dust, and other foreign matter from entering the tank and mixing into the oil therein.

The tank just described is the large steel tank commonly found in the oil fields, tank farms, around oil refineries and other oil storage places. In these tanks is stored the oil 15 from which the basic sediment 16 settles to the bottom of the tank 10 and eventually occupies a large percentage of the capacity of the tank 10. To clean the basic sediment 16 out of the tank 10 I have provided a device for stirring or circulating the oil 15 in the tank as above mentioned.

The stirring or circulating device is shown in the drawings as having a rectangular angle iron frame 17, 18, 19 and 20 and at each corner of the rectangular frame is positioned upwardly extending posts 21, 22, 23 and 24 that are rigidly attached one to each of four downwardly extending leg elements 25, 26, 27 and 28, the upper ends of which are rigidly attached each to their respective corner of the rectangular angle iron frame 17-18-19-20.

Each leg 25, 26, 27 and 28 is rigidly braced by pairs of brace members such as shown at 29 and 30, one end of each brace member being rigidly connected to its respective leg element 25, 26, 27 or 28, and the other end of the brace elements 29 and 30 being connected to their respective side or end member of the rectangular frame elements 17, 18, 19 or 20 to make the legs 25, 26, 27 and 28 stand vertical and rigid. The frame 17-18-19-20 is provided with a removable platform made of a series of planks or boards 31 laid edge to edge within the rectangular frame 17-18-19-20 with the ends of the planks or boards 31 resting in the angle of the side frame members 17 and 19 for the support thereof. A cable rope or some such element 32 is strung from top to top of the posts 21, 22, 23 and 24 to form guard or hand hold around the platform 31.

Each side frame member 17 and 19 has a pair of depending leg elements 33 and 34, the rear pair of legs 34 and 34 are joined together at their lower ends by a cross frame member 35, and the upper ends of the legs 34 and 34 are rigidly attached, riveted or welded, one to the side frame member 17 and the other to the side frame member 19, and the two legs 34 and 34 are equally spaced away from their respective corner leg elements 25 and 26. Similarly the two depending leg elements 33 and 33 are equally spaced away from the corner leg elements 27 and 28 and their upper ends are rigidly attached, riveted or welded, to their respective rectangular frame side elements 17 and 19. The end rectangular frame member 20 is provided with a hitch element 36 to which one end of a tension cable 37 may be attached for purposes that will later be explained.

The device is provided with four pairs of float elements 38-38a, 39-39a, 40-40a and 41-41a. The pairs of float elements are positioned one

pair at each corner of the rectangular frame element 17, 18, 19 and 20 and immediately below the side frame element 17 and 19 and between their respective depending leg elements 25, 26, 27 or 28 and their respective intermediate depending leg element 33 or 34. The ends of each pair of float elements are bound together by a tie bar such as shown at 42, the ends of the tie bars 42 being bolted one to each float end. Each tie bar 42 is bolted to its respective and adjacent leg element of the rectangular frame element 17, 18, 19 and 20 as a means of retaining the pairs of float elements one at each corner of the frame elements 17, 18, 19 and 20 for the buoyant support thereof.

The device is provided with any standard and suitably designed type of hydraulic motor 43. The hydraulic motor 43 is horizontally supported in a frame work 44 that is rigidly attached to side frame elements 45 and 45a, the upper ends of which are pivotally attached as shown at 46 to the upper end portions of the stationary leg elements 33 and 34, there being stop elements, not shown, on the leg elements 33 and 34 for stopping the swinging movement of the motor support frame legs 45 and 45a to normally hold the motor 43 in a horizontal position. Rigidly mounted on the outer end of the hydraulic motor drive shaft is an impeller 47.

The impeller 47 is provided with a rather vertically long and L-shaped protective screen 48, not shown in Figures 1 and 2 for purposes of more clearly showing the invention. The screen 48 is positioned one leg behind the impeller 47 and the other leg at the side of the impeller 47 as a means of shielding the impeller from foreign objects that might be carried in the flow of oil 15 that will later be described. The protective screen 48 is rigidly attached to and carried by frame elements 49 that are attached to other convenient adjacent frame members of the device. The hydraulic motor 43 has a hydraulic pressure receiving port and a hydraulic discharge port and to which ports is attached one end of a hydraulic pressure pipe line 50; and to the hydraulic discharge port is connected one end of an exhaust or discharge pipe line 51. The other ends of the pipe lines 50 and 51 are connected each to one end of a pair of flexible hose elements 52a and 51a respectively that extend to the top portion of the side wall of the tank 10 and pass through grommets 52 and 53 positioned in holes in the wall 10 and continue outside the tank 10 and connect to a hydraulic pump 54 that is preferably mounted on a motor truck frame and is driven either by a power take-off of the truck or by an independent engine 55 that is also mounted on the truck frame for purposes of making the pump 54 and power unit therefor portable so it can be moved from tank to tank for operating circulating units such as shown in Fig. 3 therein.

The rectangular frame 17-18-19-20 is provided with a pair of thrust elements A and B that are identical in construction and are attached one to each rear corner of the rectangular frame element 17-18-19-20 and extend rearwardly therefrom. The thrust elements A and B are constructed as shown in Fig. 4, and consist of a block, preferably a wood block 56 that is rigidly attached to an angle iron support 57 therefor that is rigidly attached, bolted, to one end of an adjustable two piece leg 58-59, the other end of which is rigidly attached to a hanger element 60 that is rigidly attached to

its respective frame leg element 25 or 26. The leg part 58 has an elongated slot 60 therein through which bolts 61 that are carried by the leg portion 59 pass, and nuts 62 are threaded on the bolts 61 to rigidly bind and hold the two leg parts 58 and 59 in a longitudinally adjusted position. The thrust blocks 56 are adapted to bear against the wall 10 of the tank, and by lengthening or shortening the thrust legs 58-59 the position of the frame element 17-18-19-20 can be adjusted to align the driving force of the impeller either on or to either side of the diameter line of the tank as the push of the impeller 47 pushes the frame and thrust blocks 56 rearwardly against the tank wall 10.

After the oil 15 in the tank 10 has been set in circulatory motion and the impeller has been stopped, the circulatory movement of the oil 15 will have a tendency to move or carry the circulating device from its original location in the tank. In view of this trouble I have provided the rectangular frame member 18 with a hitch element 63 that is the same as the hitch element 36, and to which one end of a cable 64 is attached. The cable 64 extends upwardly to and over a pulley 65 that is mounted at the top of, and on the wall 10 of the tank. The cable 64 then extends downwardly and a weight 66 is suspended on the free end of the cable 64. The weight 66 pulling on the cable 64, which in turn pulls on the rectangular frame 17-18-19-20 will keep the rectangular frame 17-18-19-20 substantially in place in the tank.

Tanks of the kind herein mentioned after having been in use for a considerable length of time will become corroded and weakened, and the push and vibration of the circulating device, above described, against the side wall 10 of the tank may jar the wall 10 enough to make the tank leak along some of the edges of the metal plates that compose the wall 10. In order to overcome this trouble I have provided the hitch element 36 and cable 37 attached thereto as above described, and the cable 37 extends diametrically across the tank and through a hole 67 in the upper portion of the tank wall 10. The cable 37 then continues outside the tank to and connects to an anchor element 68 that is buried in the ground. Now as the circulating device runs the push of the impeller 47 will push the rectangular frame element 17-18-19-20 rearwardly until the blocks 56 engage the tank wall 10 at which instant the slack in the cable 37 will be taken up and the heavy load of the push of the impeller 47 will be caught and absorbed by the cable 37.

Due to the fact that the oil level of the oil 15 in the tank will vary and may be high at one time of circulating the oil 15 and low at another time of circulating the oil 15, the cable 37 will have to be shortened or lengthened to fit the present existing condition, therefore the cable line 37 should have a means therein of adjusting the length of the cable. As shown in Fig. 2 this means of adjustment could be a turn buckle device 68 in the cable line 37, or as shown in Fig. 7, the adjustment device could be a hand operated windlass device 69 that is included in the cable line 37.

In Figures 5 and 6 is shown a modified form of the float elements in which the float elements have rounded or bullnosed ends 70. If desired these floats could be substituted for those shown in the other figures of the drawings. The float elements being set transversely

to that shown in the other figures of the drawings may offer less resistance to the circulating movement of the oil 15 as will later be described.

Now to prepare the device for use the device 5 may be passed, a piece at a time, through the manhole 12 in the roof of the tank and then assembled into the complete device as shown in Figures 1, 2 and 3 of the drawings. The device having thus been assembled will be supported on the pairs of float elements 38-38a, 39-39a 10 40-40a and 41-41a with the hydraulic motor 43 and impeller 47 submerged in the oil 15 and positioned below the platform planks 31, and the hydraulic pressure, and discharge lines 15 50-50a and 51-51a being connected to the hydraulic motor 43 extend to the hydraulic pump 54 as above described.

Now as the power unit 55 drives the pump 54 the pump 54 will pump or produce a hydraulic pressure in the line 50 which will be transmitted to the motor 43 which will therefore be operated to rotate the impeller 47, and the hydraulic liquid being exhausted or discharged from the motor 43 will return through the line 15 51-51a to the pump 54 for recirculation to perpetuate the hydraulic driving medium for the pump 54 and the motor 43.

The impeller 47 being driven as above described will move a volume of oil therefrom and therefore which in time will cause all the oil 15 to be in circulatory motion in the tank, and this movement of the oil 15 as top of the basic sediment 16 will eventually wear the basic sediment 16 away and it will be suspended in the oil 15 whereupon the oil 15 may be pumped from the tank 10 in the usual manner and the basic sediment 16 will be disposed of and the tank will be left free and clean of the basic sediment 16.

As the oil 15 is pumped from the tank 10 the liquid level of course will drop, and when the liquid level drops sufficiently the lower ends of the frame legs 25, 26, 27 and 28 will engage and set on the bottom of the tank and support the circulating device so that the impeller 47 will not strike the floor or bottom of the tank and thereby damage the impeller 47.

If for any reason it becomes necessary to inspect or do repair work on either the motor 43 or impeller 47, some of the centrally positioned platform planks 31 may be removed from the rectangular frame element 17-18-19-20 whereupon the motor 43 and carrying frame 44 therefor may be lifted and rocked upwardly about the pivot point 46 to raise the motor 43 and impeller 47 whereupon a man can stand on the platform 31 on either side of the motor 43 to do the necessary inspection or work. The inspection or work having been done the motor 43 may be rocked to its original position below the platform 31 and is then ready for further use the same as above described.

While the device as shown and described may be considered as the preferred form of the device, it is to be understood that such modifications of the device may be employed as lie within the scope of the appended claims without departing from the spirit and intention of the invention. Now having fully shown and described my invention, what I claim is:

1. In a liquid circulating device for use in tanks; said device having an impeller, power means for driving the impeller and float means for supporting the said power means and impeller, a frame work, said frame work being

supported on said float means, said power means and impeller being carried by a second frame structure that is carried by the first said frame work in a position below the surface of the liquid in which the said float means floats, the said frame structure being pivotally attached to the first said frame work so that the power unit and impeller may be rocked from its position below the surface of the liquid to a position above the surface of said liquid.

2. In a liquid circulating device for use in tanks; said device having an impeller, power means for driving the impeller and float means for supporting the said power means and impeller, a frame work, said frame work being supported on said float means, said power means and impeller being carried by a second frame structure that is carried by the first said frame work in a position below the surface of the liquid in which the said float means floats, the said frame structure being pivotally attached to the first said frame work so that the power unit and impeller may be rocked from its position below the surface of the liquid to a position above the surface of said liquid, a platform, said platform being made in sections and carried on the first said frame work, said platform sections being removable from the same frame work each independently of the other to make room for the elevated swinging movement of the power unit and impeller and still have sufficient platform to support a workman.

3. In a liquid circulating device for use in tanks; said device having an impeller, power means for driving the impeller and float means for supporting the said power means and impeller, a frame work, said frame work being supported on said float means, said power means and impeller being carried by a second frame structure that is carried by the first said frame work in a position below the surface of the liquid in which the said float means floats, the said frame structure being pivotally attached to the first said frame work so that the power unit and impeller may be rocked from its position below the surface of the liquid to a position above the surface of said liquid, a power development unit for developing power on which the first said power means is driven, the said power development unit being positioned outside the said tank.

4. In a liquid circulating device for use in tanks; the device defined in claim 3, said power development unit being portable for movement from tank to tank for the operation of circulating devices as described.

5. In a liquid circulating device for use in tanks; said device having an impeller, power means for driving the impeller and float means for supporting the said power means and impeller, a frame work, said frame work being supported on said float means, said power means and impeller being carried by a second frame structure that is carried by the first said frame work in a position below the surface of the liquid in which the said float means floats, the said frame structure being pivotally attached to the first said frame work so that the power unit and impeller may be rocked from its position below the surface of the liquid to a position above the surface of said liquid; and thrust means on one end of said frame work for engaging the

5 tank wall under the push of the impeller in the operation of circulating the liquid in the tank, said thrust means being adjustable to turn the circulating device to direct the line of force of the impeller on or to either side of the diametrical line of the tank.

6. In a liquid circulating device for use in tanks; said device having an impeller, power means for driving the impeller and float means 10 for supporting the said power means and impeller, a frame work, said frame work being supported on said float means, said power means and impeller being carried by a second frame structure that is carried by the first said frame work in a position below the surface of the liquid in which the said float means floats, the said frame structure being pivotally attached to the first said frame work so that the power unit and impeller may be rocked from its position 15 below the surface of the liquid to a position above the surface of said liquid; and thrust means on one end of said frame work for engaging the tank wall under the push of the impeller in the operation of circulating the liquid in the tank, said thrust means being adjustable to turn the circulating device to direct the line of force of the impeller on or to either side of the diametrical line of the tank, and means for relieving a selected amount of the thrust 20 of the device against the wall of the tank.

7. In a liquid circulating device for use in tanks, the device defined in claim 6, said means for relieving a selected amount of the thrust from the wall of the tank being a tension element, one end of said tension element being attached to the said frame work, said tension element extending diametrically across the tank and passing through the tank wall, the other end of the tension line being anchored to make 25 it stationary, and means in the tension line for adjusting its length.

8. In a liquid circulating device for use in tanks, the device defined in claim 6, said means for relieving a selected amount of the thrust from the wall of the tank being a tension element, one end of said tension element being attached to the said frame work, said tension element extending diametrically across the tank and passing through the tank wall, the other end of the tension line being anchored to make 30 it stationary and means in the tension line for adjusting its length, and means for yieldably stationing the circulating device in the tank, said means for yieldably stationing the circulating device in the tank being a flexible element, one end of said flexible element being attached to the first said frame work, said flexible element passing over a pulley carried by the upper portion of the wall of the tank, and weight means 35 attached to and supported on the other end of said flexible element as shown.
